Soled family efforts are over and we have given up our old and well-entitled in favor of a new and more comfortable one. We are now in a better position to help our children and our wife and I are very happy in our new home.

UNITED STATES PATENT OFFICE

GLOW DISC

A. J. H. VAN DER HORST

Jacob Freeman, Boston, Mass., assignor to J. Freeman, Incorporated, Boston, Mass., a corporation of Massachusetts

Application August 7, 1946, Serial No. 688,905

2 Claims. (Cl. 315—250)

This invention relates to high voltage gas discharge tubes which are usually referred to as glow discharge tubes. More particularly, the invention relates to means whereby an arrangement of two or more such tubes may be caused to light up and be extinguished repeatedly in rapid sequence. The only way known whereby this intermittent flashing of glow discharge tubes can be achieved is by the use of mechanical switches or devices external to the tubes for alternately turning on and off the current through a number of tubes. By my invention the use of such mechanical switches and other devices is dispensed with entirely, and the interruption of current through two or more discharge tubes, and hence their illumination is achieved solely by the construction and operation of the tubes themselves. My method is thus much cheaper and more reliable, and eliminates much costly equipment and expensive repair.

It is well known in the art that if a pair of high pressure metal vapor discharge tubes or a pair of low pressure gas discharge tubes of the neon gas type are connected in parallel across a high voltage circuit, only one of the pair of tubes will light up and the other will remain inoperative. This has been supposed to be due to the fact that the characteristics of such tubes are such that no two tubes have exactly the same resistance and when a discharge starts in one of the tubes, the supply voltage then is not sufficient to start the discharge in the other tube. It also is well known that the voltage required to start the discharge of such tubes when cold is much less than when hot and if the lighted tube is extinguished, due to temporary failure of the supply voltage, it will not restart at the normal supply voltage until cooled.

I have made the very surprising discovery that by connecting in parallel two or more low pressure glow discharge tubes of the neon gas type having an inside diameter much less than is commercially desirable, the tubes will light up and be extinguished repeatedly in rapid sequence provided all the tubes have the same capacity, that is, the same diameter, length and gas pressure. In accordance with my present preferred practice, I employ tubes having an inside diameter of 4 to 6 mm. and, preferably, about 5 mm., but tubes may be used having an inside diameter of from about 2 mm. up to not more than 8 mm. The length of the tube is not particularly important except that all should be the same length. It is not commercially practical to employ tubes less than 6 inches in length.

In other respects, the tubes may be constructed in accordance with the conventional practice of the art. Thus, any gas commonly employed in such low pressure tubes may be used, such as neon, argon, helium, mercury vapor, etc., or mixtures thereof. However, I prefer to use the non-metallic gases since the results are superior in many respects. The preferred gas pressure is between 2 mm. and 20 mm. of mercury.

10 I have discovered also that a unit of a plurality
of low pressure glow discharge tubes of small
inside diameter connected in parallel, as previ-
ously described, may be utilized to cause a plu-
rality of glow discharge tubes of large inside
15 diameter to light up and be extinguished re-
peatedly in rapid sequence. Thus, I may cause
the glow discharge tubes of commercial signs and
other display devices to light up and be extin-
guished repeatedly in rapid sequence. To ac-
20 complish this, the actuator unit must contain the
same number of glow discharge tubes as the dis-
play device and each of the latter tubes should
be connected separately in series with a corre-
sponding tube of the actuator unit. Further-
25 more, each of the glow discharge tubes of the dis-
play device should have the same capacity, that
is, the same length, diameter and gas pressure.
The glow discharge devices of the display device
30 may be low pressure glow discharge tubes of the
neon gas type containing neon, argon, helium,
etc., gases or mercury vapor or mixtures thereof
or they may be high pressure metal-vapor dis-
charge devices.

The invention will be more clearly understood from the following description in conjunction with the accompanying drawing in which:

Fig. 1 is a diagrammatic view illustrating one device embodying the invention; and

Fig. 2 is a diagrammatic view illustrating another device embodying the invention.

Fig. 1 illustrates one specific device embodying the invention.

45 The invention is a specific device consisting of the invention and comprises a plurality of glow discharge tubes 10, each having a length of four feet, an outside diameter of 6 mm., and an inside diameter of approximately 4 mm. They are provided at their opposite ends with electrodes 11 and 12 of Swedish iron and contain neon gas at a pressure of 4 mm. of mercury. Each of the tubes 10 are connected in parallel across the leads 50 15 and 16 which are connected to the secondary winding 17 of a standard commercial sign lighting transformer having the primary winding 18. The transformer was rated at 7500 volts and 18 milli-amperes.

55 When power was supplied to the transformer,

the tubes 10 were caused to light up and be extinguished in random sequence repeatedly, each tube being lighted up and extinguished at the rate of approximately 60 to 100 times per minute. Apparently with such tubes connected in parallel, the tube charge is built up in the tube lighted first to such a value that its starting voltage is higher than that of another tube, and another tube will be lighted in place of the first. The tube charge in the second tube then builds up, and in the previously lighted tube falls off. When more than two similar tubes are thus connected in parallel, they will light up in sequence, but not necessarily in any regular order, and thus produce a rapidly flashing light effect.

In Fig. 2 I have illustrated a unit A of the type illustrated in Fig. 1 as an actuator for a commercial display unit D.

In the device illustrated in Fig. 2, the unit A comprises a plurality of glow discharge tubes 10' having the same specifications as the tubes 10 of Fig. 1. The tubes 10' are connected in parallel across the leads 15' and 16' which are connected to the secondary winding 17' of a standard commercial sign lighting transformer having the primary winding 18'. The transformer was rated at 7500 volts and 18 milliamperes. The display device D comprises a plurality of glow discharge tubes 20 having the usual electrodes 21 and 22 and are connected in series with each of the tubes 10'. As illustrated, the electrode 12' of each of the tubes 10' is connected to the lead 15' by a lead 23 and each of the electrodes 11' is connected to the adjacent electrode 22 of the corresponding tube 20 by a lead 24. The other electrode 21 of each of the tubes 20 is connected by a lead 25 to the lead 16'. When power was supplied to the transformer, each tube 10' and the device 20 connected in series with it was caused to light up and be extinguished together and the devices 20 were caused to light up and be extinguished in random sequence repeatedly in substantially the same manner as in the device shown in Fig. 1.

It will be understood that the devices 20 may be of any type commonly employed in commercial signs or display devices to form letters or other characters, symbols, etc. Thus, the device 20 may be high-pressure metal vapor discharge devices, but, in any case, all of the devices 20 should be of the same capacity, that is, the same length, same diameter and same gas pressure. The actuating unit A may be positioned at any place remote from the display device D, and if compactness is desired, the low-pressure glow discharge tubes 10' may be short, for example, about two feet in length, but for practical reasons, their length should be greater than six inches.

It will also be understood that the capacity of the transformer employed is determined by the capacity of the tubes 10' and the devices 20, as will be readily understood by those skilled in the art.

I claim:

1. In combination, a plurality of similar low pressure glow discharge tubes of the neon gas type, each having the same diameter, same length and same gas pressure, means for electrically connecting said tubes in parallel, each of said tubes having an inside diameter between about 2 mm. and 8 mm. whereby when said means is connected to a source of electrical energy suitable to cause any of said tubes to light up they will light up and be extinguished repeatedly in rapid sequence, and another glow discharge tube having an inside diameter greater than 8 mm. electrically connected in series with each of said low pressure tubes, each of the tubes of largest diameter having the same length, same gas pressure and same diameter whereby each will light up and be extinguished with the low pressure tube with which it is connected in series.
2. In combination a plurality of similar low pressure glow discharge tubes of the neon gas type, each having the same diameter, same length and same gas pressure, means for electrically connecting said tubes in parallel, each of said tubes having an inside diameter between 4 and 6 mm. whereby when said means is connected to a source of electrical energy suitable to cause any of said tubes to light up they will light up and be extinguished repeatedly in rapid sequence, and another glow discharge tube having an inside diameter greater than 8 mm. electrically connected in series with each of said low pressure tubes, each of the tubes of largest diameter having the same length, same gas pressure and same diameter whereby each will light up and be extinguished with the low pressure tube with which it is connected in series.
